(57) CLAIM

The ornamental design for a smart ring, as shown and described.

DESCRIPTION

FIG. 1 is a front perspective view of a smart ring showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The dot-dash broken lines in the figures represent a boundary of the claimed design and form no part of the claimed design. The remaining broken lines in the figures depict portions of the smart ring that form no part of the claimed design.

1 Claim, 6 Drawing Sheets
